UNITED STATES PATENT OFFICE

HERBERT V. HENDERSON, OF DETROIT, MICHIGAN, ASSIGNOR TO CHRYSLER CORPORATION, OF DETROIT, MICHIGAN, A CORPORATION OF DELAWARE

DESIGN FOR A RADIATOR SHELL

Application filed September 10, 1930. Serial No. 36,927. Term of patent 14 years.

To all whom it may concern:

Be it known that I, HERBERT V. HENDERSON, a citizen of the United States, residing in the city of Detroit, county of Wayne, and State of Michigan, have invented a new, original, and ornamental Design for a Radiator Shell of which the following is a specification, reference being had to the accompanying drawings, forming a part thereof, in which—

Fig. 1 is a perspective view of the radiator shell showing my new design.

Fig. 2 is a side elevation of the radiator shell shown in Fig. 1.

Fig. 3 is a sectional view on line 3—3 of Fig. 2.

Fig. 4 is a fragmentary view showing the upper portion of the radiator enlarged and in perspective.

I claim:

The ornamental design for a radiator shell substantially as shown.

HERBERT V. HENDERSON.
